US0D1054954S

(12) **United States Design Patent** (10) Patent No.: **US D1,054,954 S**
Kalha (45) Date of Patent: ** Dec. 24, 2024

(54) **VEHICLE WHEEL RIM**

(71) Applicant: **VOLKSWAGEN AKTIENGESELLSCHAFT**,
 Wolfsburg (DE)

(72) Inventor: **Ranbir Kalha**, Wolfsburg (DE)

(73) Assignee: **VOLKSWAGEN AKTIENGESELLSCHAFT**,
 Wolfsburg (DE)

(**) Term: **15 Years**

(21) Appl. No.: **29/890,819**

(22) Filed: **Apr. 27, 2023**

(30) **Foreign Application Priority Data**

Feb. 3, 2023 (DE) 40 2023 100 051.3
